UNITED STATES PATENT OFFICE

114,960

DESIGN FOR A SOUND-PROJECTOR FOR AUTOMOBILE HORNS OR THE LIKE

Peter Nielsen, Omaha, Nebr., assignor to Jubilee Manufacturing Company, Omaha, Nebr., a corporation of Nebraska

Application August 1, 1938, Serial No. 78,996

Term of patent 7 years

To all whom it may concern:

Be it known that I, Peter Nielsen, a citizen of the United States, residing at Omaha, in the county of Douglas and State of Nebraska, have invented a new, original, and ornamental Design for a Sound-Projector for Automobile Horns or the like, of which the following is a specification, reference being had to the accompanying drawing, forming part thereof.

Figure 1 is a plan view of a sound-projector for automobile horns or the like, showing my new design.

Figures 2 and 3 are, respectively, a perspective and an end view thereof.

I claim:

The ornamental design for a sound-projector for automobile horns or the like, as shown.

PETER NIELSEN.
